[57] ABSTRACT

A support means adapted to be attached to a ladder to provide a platform operable for supporting an operator or other desirable means while the ladder is in use and includes a frame attachment assembly which will permit the platform to be moved from an operable supporting position to a displaced nonsupporting position to allow ascending and descending movement relative thereto along the ladder. The frame assembly includes a pair of bracket supports members pivotally supported for movement from a laterally displaced nonsupporting position to a fore and aft operable supporting position with the platform supporting surface in contact with an upper edge of the support brackets. The frame assembly includes means for removably attaching the platform support means to the rungs of a ladder. A safety ring supporting means defining a supporting area around the path of ascending and descending movement along the ladder is removably attached to the ladder in vertically spaced location relative to the platform support means to provide safety means for an operator standing on the platform support means.

LADDER PLATFORM ATTACHMENT**BACKGROUND OF THE INVENTION**

This invention relates to the building construction and finishing industry wherein a ladder is used to allow a construction worker to reach a predetermined area in a building construction or finishing operation. More particularly, this invention includes a platform attachment which can be readily attached to a ladder to provide a supporting surface for an operator using the ladder, allowing the operator to stand thereon at a predetermined location.

In the building construction and finishing industry a ladder is often used to allow an operator to reach a desired location to perform a building construction task such as adding or removing construction elements to a building or for use in painting a desired area of a building. A number of ladder support means and attachments have been provided which will provide a supporting surface for an operator to stand thereon when attached to a ladder. However, the prior art ladder platform support attachments have been extremely complex in construction, uneconomical to manufacture and unreliable in performance.

Further, the prior art ladder platform support attachments must be completely removed from a supporting ladder to allow an operator to have ascending and descending motion along the ladder. Such a platform attachment must allow an operator to ascend to a desired location and then the platform support attachment must be attached to the ladder by an additional operator.

SUMMARY OF THE INVENTION

The above disadvantages of the prior art have been overcome by the present invention which basically includes a frame assembly having means for supporting engagement with a ladder. The frame assembly includes a pair of bracket support means pivotally supported thereon for movement from a laterally extending inoperable position to a fore and aft supporting position. A platform support surface is removably attached to one of said bracket members and adapted to be moved to a supporting position in contact with an upper edge of the bracket support members when moved to an operable support position.

An important feature of the present invention is the location of the bracket support means relative to the width of the ladder whereby movement of the bracket support members and platform support surface to an inoperable position will allow ascending and descending movement relative thereto along the length of the ladder.

An additional feature of the present invention includes the angular relationship of the pivotal axis of the bracket support means, whereby the support brackets are urged and maintained in an operable supporting position by the weight of an operator standing on the support platform.

Another feature of the present invention includes a safety ring supporting member adapted to be attached to a ladder in vertically spaced location relative to the platform support means and wherein the ring support means is provided with a detailed supporting surface surrounding the outer edge of the platform support surface to provide a safety support means for an operator

standing on the platform. The safety ring support member is supported on the ladder for movement from an inoperable position to an operable position allowing an operator to move into position on the support platform and thereafter moving the safety ring to an operable position.

It is therefore a primary object of this invention to provide a platform support means which can be readily attached and removed from a ladder.

Another object of this invention is to provide a platform support means having a platform support surface which can be moved from an operable supporting position located in the path of ascending and descending movement along the ladder and can be moved to an inoperable position located outwardly from the path of ascending and descending movement along the path of the ladder.

Another object of this invention is to provide a frame assembly which can be readily attached to a ladder and which includes support means permitting a platform support surface to be supported thereon in an operable position and to be moved to a laterally displaced inoperable position.

A still further object of this invention is to provide a frame supporting assembly for supporting a platform surface on a ladder whereby the weight of an operator standing on the platform will urge the frame assembly to an operable supporting position.

Still another object of this invention is to provide a frame supporting assembly which can be readily removed or attached to the rungs of a ladder.

Yet another object of this invention is to provide a frame assembly adapted to be attached to the rungs of a ladder whereby the frame assembly includes adjusting means allowing the frame assembly to be connected to the rung of a ladder at a number of selected laterally spaced positions.

Another object of this invention is to provide a safety support member adapted to be attached to a ladder for providing a safety means surrounding the path of ascending and descending motion along the ladder to aid in retaining an operator in position on the ladder.

A further object of this invention is to provide a safety means for attachment to a ladder which can be moved between operable and inoperable positions.

An additional object of this invention is to provide a number of ladder attachment means which are light weight, simple in construction and assembly, economical to manufacture and reliable in performance.

These and other objects and advantages of the details of construction will become apparent upon reading the following description of the illustrative embodiments with reference to the attached drawings wherein like reference numerals have been used to refer to like parts throughout the several figures, and wherein:

BRIEF DESCRIPTION OF THE DRAWINGS

FIG. 1 is a fragmentary perspective view of a ladder showing the platform support means of the illustrative embodiments attached thereto and moved to an inoperable nonsupporting position and with the safety ring support member supported on the ladder in vertically spaced location relative to the platform support means;

FIG. 2 is an exploded perspective view as seen from the rear of the platform support means shown in FIG. 1 and with the platform supporting surface moved to an operable supporting position;

FIG. 3 is an enlarged fragmentary perspective view of the safety ring support means, with certain parts being broken away and shown in section for purpose of clarity;

FIG. 4 is a vertical sectional view taken longitudinally along the length of the ladder showing the platform support means and safety ring means moved to an operable supporting position.

DESCRIPTION OF THE ILLUSTRATIVE EMBODIMENTS

Referring now to the drawings, the illustrative embodiments of the present invention will be described with reference to a conventional ladder represented generally by the reference numeral 10. The ladder includes a pair of parallel arranged leg members 11, 12 which are connected in spaced apart relationship by a series of vertically spaced rungs 13. One illustrative embodiment of the present invention includes a support platform 20 having a frame attachment assembly 25 which can be easily attached to the ladder 10 for use in providing a support surface for an operator using the ladder either to stand on or to provide a support for equipment used in a building construction or finishing operation. A second illustrative embodiment of the present invention includes a safety ring support means 60 having a support bracket 70 whereby the safety ring can be readily attached to a conventional ladder 10. The function of the safety ring mechanism 60 is to allow the ring to be supported at a position vertically spaced above the platform 20 whereby the ring would provide a guard rail surrounding the area of movement above platform 20.

As shown in FIGS. 1, 2 and 4, the support platform attachment 20 includes frame attachment assembly 25. The frame attachment assembly 25 includes a pair of laterally spaced vertically oriented bracket elements 26, 27. The opposite ends of each of the brackets 26, 27 are provided with inverted or downwardly oriented substantially V-shaped support members 28. Support members 28 are detailed for receiving the rungs 13 of a ladder, as shown in FIG. 4. The V-shaped support members 28 are detailed in the V-shaped design to permit a number of various sizes of ladder rungs to be inserted or received therein. Vertically extending brackets 26, 27 are supported in laterally spaced relationship by means of a pair of horizontally oriented and parallel arranged angle members 29, 30. Angle members 29, 30 are fixed by conventional means such as welding to bracket 27 and are connected to the bracket 26 in laterally spaced relationship by means of a slot and bolt connection. Each of the angle members 29, 30 is provided with an elongated slot 31, 32, respectively detailed for readily receiving a complementary wing nut connecting means 33, 34, respectively. Slots 31, 32 and wing nut connections 33, 34 are detailed to permit lateral adjustment of bracket 26 relative to bracket 27.

When the bracket 26 is moved to a selected position, adjustment of the wing nut 33, 34 will securely clamp and hold bracket 26 in a fixed position relative to the angle members 29, 30.

As shown in FIG. 2, the angle member 29 is detailed in length to be substantially equal to the width of a ladder with the angle support bracket 30 detailed in length to extend laterally outward on opposite sides of the ladder, for providing a pivotal support for support brackets, as will be described in more detail herein below.

Platform 20 is supported from the attachment assembly 25 by means of a pair of pivotally mounted support brackets 35, 36. Each of the support brackets 35, 36 includes an upper supporting rod 37, a lower bracing rod 38 and a number of vertically extending spacing rods 39. Each of the upper support rods 37 includes an extended end portion which is bent downward a slight distance to provide a pivotal supporting stud 40. The pivotal support studs 40 are detailed to be substantially coplanar to the vertically extending rods 39 and substantially parallel arranged thereto.

As shown in FIGS. 1 and 3, each of the lower bracing support rods 38 include an extended end which is bent in a first direction laterally outward and includes a formed end portion bent downward to provide a second pivot support stud 41. The pivot support studs 41 are detailed to be parallel to the pivot support studs 40 and laterally spaced outwardly in substantially a common plane. As shown in FIG. 1, the pivot support studs 40, 41 are pivotally received within openings (not shown) provided in the angle members 29, 30, respectively. The pivotal openings for pivot stud 40 are defined in a horizontal surface of angle member 29 adjacent the lateral extended edges thereof and the pivotal opening for pivotal stud 41 are provided in a horizontal surface of angle member 30 adjacent laterally extended edges thereof.

As shown in FIGS. 1 and 2, the support brackets 35, 36 are attached to angle members 29, 30, respectively, whereby they can be pivoted from a laterally extended substantially coplanar inoperable position to a fore and aft substantially parallel arranged operable supporting position. When the support brackets 35, 36 are moved to their laterally extending operable position, they extend laterally outward from opposite sides of the ladder 10 to provide an unobstructed ascending and descending path of movement there along. When the support brackets 35, 36 are moved to the fore and aft operable supporting position, the support platform 20 and brackets 35, 36 provide a supporting surface for an operator using the ladder and will prevent ascending and descending movement relative thereto.

As shown in FIGS. 1 and 2, the support platform 20 includes an elongated wedge-shaped element 21 which is fixed along one lateral edge thereof. The elongated wedge-shaped element 21 is removable received by a complementary wedge-shaped socket portion 22 fixed to the upper supporting rod 37 of support bracket 35. The wedge member 21 and socket member 22 are detailed to allow the platform 20 to be readily removed from the attachment frame assembly 25 by sliding the platform to the right, as shown in FIG. 1, to withdraw wedge member 21 from socket 22.

When the bracket support members 35, 36 are moved to an operable fore and aft supporting position, one lateral side edge of platform 20 will be connected by wedge 21 and socket 22 to be supported by the angle bracket 35 and an opposite lateral side edge of

platform 20 will be supported in abutting contact with the upper surface of support rod 35 of the angle bracket 36. Platform 20 is provided with a safety rail 23 extending around a portion of the lateral sides thereof. The safety rail 23 is provided to prevent objects or a person standing on the platform from being easily displaced over the lateral edges thereof.

In operation, the frame attachment assembly is connected to a supporting ladder by inserting the inverted V-shaped receiving members 28 of brackets 26, 27 over the rungs of a ladder. After the brackets 26, 27 have been positioned in supporting engagement with the rungs of a ladder, the bracket 26 is laterally adjusted relative to bracket 27 to a desired laterally adjusted position. After the brackets 26, 27 have been moved to a desired lateral set position the adjustable wing nuts 33, 34 are securely tightened to clamp the bracket 26 relative to the angle support members 29, 30.

With the support frame attachment assembly 25 supported on a ladder as indicated above, the two support brackets 35, 36 are attached thereto by inserting the pivot studs 40, 41 in their respective pivot receiving openings provided in angle members 29, 30. After the angle support bracket 35, 36 have been mounted within the pivot openings, the support platform 20 is connected to the angle bracket 35 by inserting wedge member 21 within the socket 22.

When using the platform attachment 20, the bracket members 35, 36 are moved to their laterally extending inoperable position as shown in FIG. 1 to allow an operator to ascend the rungs of the ladder and reach a desired position thereon. After the operator has reached a position above platform 20, the operator can pivot brackets 35, 36 to a fore and aft operable supporting position wherein the platform 20 will be attached to the bracket 35 and will be moved into abutting contact with the upper supporting rod 37 of bracket 36. In the operable supporting position, an operator can stand on the platform 20 to perform a number of construction or building finishing operations, as required. Further, if the operator does not desire to stand on the platform 20, the platform 20 can be used for supporting various equipment which is used in the construction and finishing of a building.

Should an operator located above the platform 20 desire to descend ladder 10, the operator would pivot support brackets 35, 36 to their laterally extending inoperable positions. Movement of brackets 35, 36 to their laterally extending inoperable position would also move the platform 20 to a position displaced laterally outward of the path of ascending and descending movement along ladder 10, whereby the operator could descend the ladder to a desired location.

After an operator has finished using the ladder 10 or finished using the platform support attachment 20, the attachment can be readily removed from the ladder by merely lifting the platform attachment support assembly 25 vertically upward to displace the inverted V-shaped receiving elements 28 from the rungs of the ladder 13. After the support attachment 25 has been removed from the ladder, the frame assembly 25 and platform 20 can be completely disassembled for easy storage and transport to additional desired locations.

Referring now particularly to FIGS. 1, 3 and 4, one illustrative embodiment of the present invention includes a safety supporting ring member 60. The safety supporting ring member 60 is constructed of a substantially U-shaped member having a base 61 with a pair of extending parallel arranged legs 62, 63. The base member 61 is detailed in dimensions to support legs 62, 63 on opposite lateral side edges of the ladder legs 11, 12, as shown in FIG. 1. The length of legs 62, 63 are detailed in dimensions to allow the base portion 61 to be displaced to the right, as shown in FIG. 4, to allow a path of ascending and descending movement relative to the ladder. The dimensions of the safety ring 60 are also detailed such that they will provide a ring support member extending around the lateral sides of the platform 20, described herein above, whereby an operator standing in position on the ladder 20 can be maintained within the safety ring 60 to allow the operator to perform various tasks without falling off of the support platform 20.

The safety ring means 60 is supported on ladder 10 by means of a mounting attachment 70. The mounting attachment 70 includes a pair of laterally extending telescoping tubular sections 71, 72. As shown in FIG. 1, the tubular section 71 is slidably received within tubular section 72 to allow lateral adjustment relative to each other. Each of the tubular sections 71, 72 are provided with a substantially J-shaped connecting bolt 73. The J-shaped connecting bolts 73 are provided with a curved ladder rung engaging portion 74 and an elongated shank portion 75. The elongated shank portion 72 is detailed for extending through a complementary opening provided in the respective tubular sections 71, 72. An extended end of the shank portion 75 is provided with conventional adjusting threads 76 detailed for receiving a conventional wing adjusting nut 77.

In attaching the support attachment 70 to a ladder, the J-shaped formed portions 74 are inserted around the rungs 13 of a ladder, as shown in FIG. 4, with the shank portion 75 extending through the tubular section 71, 72. After the J-shaped bolts 73 have been moved to a desired laterally set position, the wing nuts 77 are tightened on the shanks 76 to securely clamp the support attachment 70 to a supporting ladder rung 13.

The extending outer end of each of the tubular sections 71, 72 are provided with an upstanding angle support bracket 80, which is fixed to the tubular section by conventional means such as welding (not shown). The angle support brackets 80 includes a first surface portion 81 which is detailed for abutting engagement with the back side of the legs of the ladder, as shown in FIG. 4. Extending forwardly from surface 81 is a second surface portion 82 disposed at substantially right angle to surface 81. The angle surfaces 82 are provided with a slot receiving means for receiving the releasable connecting elements 65 formed on the extended end of each of the safety ring legs 62, 63, as shown in FIG. 3.

The slot receiving means of bracket 80 includes a first vertically oriented slot 83 and a second horizontally oriented slot 84. The slots 83, 84 are connected to each other adjacent one edge thereof. The receiving slots 83, 84 and the releasable connecting elements 65 of the ring 60 are detailed to provide a bayonet type releasable connecting means whereby the safety ring 60 can be moved to a vertically oriented position sub-

stantially aligned with the vertical slot 83. With the leg members 62, 63 in a vertically aligned position, the connecting element 65 can be inserted within or removed from the vertical slots 83. After the connecting element 65 has been inserted within the vertical slots 83, the safety ring member is pivoted to a downward or rightwardly extended position, as shown in FIGS. 1 and 4 whereby the connecting element 65 will be rotated to a latched position within the horizontally oriented slot 84. The releasable connecting element 65 includes an extended formed tab portion 66 which will maintain the connecting element 65 within slot 84 when the safety ring means is moved to a horizontally oriented operable supporting position. The dimensions of the vertical slot 83 and the length of the connecting element 65 including tab 66 are detailed to permit the connecting element 65 to be readily received and withdrawn through the slot 83 when the safety ring is in a vertically displaced inoperable position.

The safety ring 60 including base member 61 and legs 62, 63 are constructed of a conventional metal tubular stock material which will permit a limited amount of flexing movement of the legs 62, 63 to an outward position to permit the connecting elements 65 to be aligned with the vertical slots 83. The tension within legs 64, 65 will urge the connecting elements 65 inwardly to a connected position within slot 83. After the connecting elements 65 have been inserted within slots 63, the rotary movement in a clockwise direction as shown in FIGS. 3 and 4, will move the connecting elements 65 to the latched position within the retaining slot 84.

It is to be noted that the ladder platform support attachment 20 can be used with or without the safety ring member 60 and the safety ring member 60 can be used with or without platform support attachment 20. Further, the safety ring 60 could be supported on the ladder 10 by using an attachment assembly similar to the assembly 25 shown in FIG. 2 wherein the safety ring 60 could be quickly attached to the ladder rungs 13 without the use of adjustable connecting bolts 73. This would be accomplished by fixing the support brackets 80 to opposite ends of an angle member 29 and allowing the V-shaped brackets 28 to be inserted over the rungs of a ladder.

It now becomes apparent that the above described illustrative embodiments are capable of obtaining the above stated objects and advantages. It is obvious that those skilled in the art may make modifications in details of construction without departing from the spirit of the invention which is to be limited only by the scope of the appended claims.

What is claimed is:

1. A platform support means capable of attachment to a ladder comprising side rails and rungs, comprising in combination:

- a. a frame assembly adapted to extend across the space between the side rails of the ladder;
- b. means for supporting said frame assembly on a ladder;
- c. a first support bracket mounted on said frame assembly and adapted, when said assembly is positioned on a ladder, to project away from the ladder in a plane adjacent one side rail of the ladder and

perpendicular to the plane of the rungs of the ladder;

- d. a second support bracket pivotally mounted on said frame assembly for swinging movement from a position adjacent the other rail of said ladder and perpendicular to the plane of the rungs to a second position outwardly of said other rail and substantially in the plane of the rungs; and
- e. a platform member carried by said second support bracket and adapted, when said bracket is in its first position, to extend across the ladder and rest on said first support bracket and, when said second support bracket is in its second position, to lie entirely beyond the rungs of the ladder, to permit free movement of a person up or down said ladder.

2. A platform support means as in claim 1 wherein said first support bracket is pivotally mounted for movement from the position described in claim 14 to a second position in which said first support bracket lies outwardly of the ladder and substantially in the plane of the rungs.

3. A platform support means as in claim 1 wherein said platform member is detachably mounted on said second support bracket.

4. A platform support means as in claim 2 wherein the pivotal connections between said frame assembly and said support brackets comprise pivot studs secured to said support brackets and openings in said frame assembly adapted to receive said pivot studs.

5. A platform support means as described in claim 1 further characterized in that said frame assembly includes means for attaching said frame assembly to the rungs of a ladder.

6. A platform support means as described in claim 5 further characterized in that said rung attachment means includes a pair of laterally spaced support members and wherein said laterally spaced support members includes means for mounting at least one of said support members for lateral adjustment relative to said other support member.

7. A platform support means as described in claim 6 further characterized in that said rung attachment means includes means for removably attaching said frame assembly to at least two spaced rungs.

8. An operable safety support means capable of attachment to a ladder comprising, in combination; a substantially U-shaped retaining member, means for removably supporting said U-shaped retaining member from a ladder whereby said U-shaped member extends outwardly from a ladder to define a supporting ring surrounding the path of ascending movement along said ladder, said supporting means including a support bracket adapted to be attached to said ladder and wherein said support bracket includes releasable connecting means adapted to be connected to opposite leg portions of said U-shaped member.

9. An operable safety support means as described in claim 8 further characterized in that said ring support member is pivotally mounted for movement relative to said support means for movement from an upwardly displaced inoperable position disposed substantially parallel to said ladder to a downwardly displaced operable position disposed substantially at right angles to the plane of said ladder.

10. An operable safety support means as described in claim 8 further characterized in that said supporting ring includes releasable connecting elements formed on an extended end of each of said U-shaped leg members and wherein said ladder attachment means includes a pair of socket members detailed for readily receiving said connectable elements and wherein said legs of said ring member are movable from an outwardly disconnecting position allowing said connecting elements to be removed from said sockets and to an inward position allowing said connectable elements to be inserted in said receiving socket.

11. An operable safety support means as described in claim 10 further characterized in that said socket

receiving means includes a first slot portion detailed for maintaining said leg connecting elements in a connected position when said supporting ring is moved to said operable position and wherein said socket receiving means includes a second slot portion detailed for permitting said connectable elements to be removed therethrough when said ring is moved to said displaced inoperable position.

12. An operable safety support means as described in claim 8 further characterized in that said means for removably mounting said support means on a ladder includes laterally spaced connecting elements adapted to be adjustably secured to the rung of a ladder.
